US0D1085450S

(12) United States Design Patent (10) Patent No.: US D1,085,450 S
(45) Date of Patent: * Jul. 22, 2025

(54) DEVICE FOR MASSAGING SCALP

(71) Applicant: Shenzhen Breo Technology Co., Ltd.,
Shenzhen (CN)

(72) Inventor: Fei Du, Guangdong (CN)

(73) Assignee: Shenzhen Breo Technology Co., Ltd.,
Shenzhen (CN)

() Term: 15 Years

(21) Appl. No.: 35/517,436

(22) Filed: Apr. 7, 2023

(80) Hague Agreement Data

Int. Filing Date: Apr. 7, 2023

Int. Reg. No.: DM/228847

Int. Reg. Date: Apr. 7, 2023

Int. Reg. Pub. Date: Jun. 9, 2023

(30) Foreign Application Priority Data

Dec. 9, 2022 (CN) 202230827121.9

(57) CLAIM

The ornamental design for a device for massaging scalp as shown and described.

DESCRIPTION

1. Device for massaging scalp

1.1: Front

1.2: Back

1.3: Left

1.4: Right

1.5: Top

1.6: Bottom

1.7: Perspective

1.8: Perspective

Figs. 1.1 to 1.8 are drawings showing the device for massaging scalp.

The broken lines form no part of the claimed design.

1 Claim, 8 Drawing Sheets
